UNITED STATES PATENT OFFICE.

HARVEY ZWINGLE MORGAN, OF PINE BLUFF, ARKANSAS.

COMBINED TIE AND RAIL FASTENER.

Application filed January 25, 1924. Serial No. 688,534.

To all whom it may concern:

Be it known that I, HARVEY Z. MORGAN, a citizen of the United States, residing at Pine Bluff, in the county of Jefferson, State 5 of Arkansas, have invented certain new and useful Improvements in Combined Tie and Rail Fasteners, of which the following is a specification.

My invention relates to a combined tie 10 and rail fastener and it consists in the combinations, constructions and arrangements herein described and claimed.

An object of the invention is to provide a device of the character described which 15 embodies conveniently operable renewable means for releasably holding a rail on the body of the device without there being any necessity of making use of the usual spikes or similar fastening devices.

20 A further object of the invention is to provide a device of the character described which is not likely to get out of order easily, is strong and durable in construction, and is thoroughly practical commercially.

25 Other objects and advantages will be apparent from the following description, considered in conjunction with the accompanying drawings, in which:

Figure 1 is a perspective view of a practical embodiment of the invention with two spaced-apart parallel rails in position thereon,

30 Figure 2 is a perspective group view showing the separable elements at one end 35 of the device detached from one another,

Figure 3 is a transverse section through the device with the separable elements of the device assembled, the view being taken substantially along the line 3—3 of Figure 40 2, and

Figure 4 is a section on the line 4—4 of Fig. 2.

A tie embodying the invention comprises a body 1 which may be formed of any suitable material, such as wood, or metal. The tie body 1 is shown as being substantially rectangular in cross sectional contour although obviously it may have any desirable shape in cross section without departing from the spirit and scope of the invention, as will presently appear.

The tie body is provided adjacent to each of its opposite ends with a recess or socket 2 opening through the upper face thereof, each of the recesses or sockets 2 being circular in cross sectional contour and each

having a flat bottom 3. A circular disc 4 is rotatably received in each socket 2 and rests upon the bottom 3, the disc being of such diameter as to closely interfit the socket 60 or recess and being of less thickness than the depth of the socket or recess so that the upper face of the disc will be disposed at a lower level than the plane of the upper face of the tie body. Each disc may be 65 retained against vertical displacement from the recess in which it is disposed by retaining members 5 which are partially received in grooves or channels 6 opening through the upper side of the tie body and which 70 extend inwardly beyond the wall of each recess or socket in overlying contiguous relation to the disc in such socket. The retaining members 5 may be held against accidental displacement from the grooves 75 or channels 6 in any suitable known manner, no means therefor being shown in the drawings. Each disc has notches 7 extending inward from its periphery and corresponding in number and arrangement with the 80 retaining members 5, each notch 7 being of slightly greater width and length than the extending portion of the corresponding retaining member 5 so that the disc 4 may be lifted bodily when it has been rotated to 85 such position in the socket in which it is disposed that the inwardly extending portions of the retaining members 5 will enter the notches 7 and thus permit the aforesaid vertical displacement of the disc. How- 90 ever, when the disc is in any other position in the socket in which it is disposed, the extending portions of the retaining members will engage with the upper side of the disc and prevent vertical displacement 95 of the latter.

Each end portion of the tie is provided with a pair of rail seats 8 which are aligned transversely of the tie body and are formed by cutting channels in the tie body to extend from the side walls of the tie body through the wall of the adjacent socket or recess 2 at diametrically opposite points. Each rail seat 8 lies in a plane substantially co-incident with the plane of the upper 100 side of the disc 4 which is disposed in the socket with which such rail seat is associated, whereby the disc will aid in supporting a rail which is arranged to extend across the tie body to rest upon a pair of 105 rail seats 8 and the disc 4, the frictional engagement of the rail with the disc being

sufficient to prevent accidental rotational movement of the disc, although insufficient to prevent rotation of the disc when a torque is applied to the latter.

5 Each disc 4 is provided with a pair of upstanding co-operative clamping lugs 9 and 10, respectively. These lugs are located diametrically opposite each other on the upper side of the disc and adjacent to the 10 peripheral edge of the disc, the respective lugs having faces, indicated at 9^a and 10^a, respectively which lie in vertical planes extending through the disk 4 in spaced parallel relation to each other and at opposite 15 sides of a diametrical line on the upper face of the disk, the respective faces 9^a and 10^a being undercut to closely engage with the upper and edge portions of opposite sides of the base flange of the rail 11 which 20 extends across one of the discs 4 and its associated rail seats 8, the engagement of the lugs with the rail occurring only when the disc has been rotated to the position shown in Figures 1 and 3 of the drawings. 25 It will be manifest that the rail will be securely clamped to the tie body when the disc 4 is in the position just mentioned since the clamping lugs 9 and 10 partially overlie opposite side portions of the base flange 30 of the rail. Each disc 4 may be releasably held in rail-fastening position through the agency of a spring locking key 12 which may be inserted through a horizontal opening 13 in one end of the tie body into a 35 socket or recess 14 in the peripheral wall of the adjacent disc 4. Each locking key 12 is formed of a piece of spring wire bent substantially into V-shape and the opening 40 13 preferably decreases in width towards its inner end as does the recess or socket in the associated disc so that the arms of the locking member will be inherently actuated because of the spring qualities of the material of which the locking member is composed 45 to spring apart and to thus engage with the side walls of the opening 13 and the socket 14 when the locking member has been inserted to the position clearly shown in Figure 4 of the drawings and is then released. 50

From the foregoing description of the various parts of the device, the operation thereof may be readily understood. The rails held on the tie body cannot move vertically or laterally because of the engagement of the clamping projections 9 and 10 when the latter are in rail-engaging position. It will be observed that each of the clamping projections 9 or 10 tends to force the rail 55 against the confronting or opposite side wall of the adjacent rail seat 8 so that very little, if any, stress will be placed on the locking member 12 when the disc 4 is locked by the latter in rail-securing position. In order 60 to release each rail, it only is necessary to 65

force the extending arms of the locking member toward each other to permit withdrawal of the locking member and to then bodily rotate the disc 4 associated with the rail until the clamping projections 9 and 10 have been moved out of engagement with the base flange of the rail. 70

One of the arms of the locking key 12 may have a projection indicated at 12' engageable with a notch in the wall of the 75 socket 13 and thus tending to prevent displacement of the locking key from locking position.

Obviously, my invention is susceptible of embodiment in forms other than that illustrated in the accompanying drawings and I, therefore, consider as my own all modifications and adaptations of the form of the device herein illustrated and described as fairly fall within the scope of the appended 80 claims. 85

I claim:

1. A combined tie and rail fastener comprising a body having recesses opening through the upper wall thereof adjacent to opposite ends of the tie body, each recess being circular in horizontal section, a rotatable disc interfitting each recess and terminating below the plane of the upper end of the recess, rail-engaging projections 90 upstanding from the disc for engaging opposite sides of a rail when the disc has been rotated to a certain position in respect to a rail extending thereacross, and means for releasably holding the disc in such position in 100 the recess in which it is disposed that said projections remain in engagement with said rail. 105

2. A combined tie and rail fastener comprising a body having recesses opening through the upper wall thereof adjacent to opposite ends of the tie body, each recess being circular in horizontal section, a rotatable disc interfitting each recess and terminating below the plane of the upper end of the recess, rail-engaging projections upstanding from the disc for engaging opposite sides of a rail when the disc has been rotated to a certain position in respect to a rail extending thereacross, said disc having 110 a socket in the peripheral wall thereof and said tie body having an opening in an end thereof extending through the wall of the recess in which the disc is disposed, said opening being in register with the socket in 115 the disc when the latter is in rail-securing position, and a key insertable through said opening into engagement with the socket in the peripheral wall of said disc. 120

3. A combined tie and rail fastener comprising a body having recesses opening through the upper wall thereof adjacent to opposite ends of the tie body, each recess being circular in horizontal section, a rotatable disc interfitting each recess and termi- 125 130

- nating below the plane of the upper end of the recess, rail-engaging projections up-
standing from the disc for engaging oppo-
site sides of a rail when the disc has been
5 rotated to a certain position in respect to a
rail extending thereacross, means for releas-
ably holding the disc in such position in the
recess in which it is disposed that said pro-
jections remain in engagement with said
10 rail, said disc having a socket in the periph-
eral wall thereof and said tie body having an
opening in an end thereof extending through
the wall of the recess in which the disc is
disposed, said opening being in register with
15 the socket in the disc when the latter is in
rail-securing position, and a spring locking
member insertable through the opening in
the end of the tie body into frictional en-
gagement with the walls of said socket in
20 the disc.
4. A combined tie and rail fastener com-
prising a body having a recess in the upper
side thereof adjacent to one end thereof;
said recess being circular in horizontal sec-
tion, a disc rotatably supported in said re-
cess and terminating at its upper end below
25 the plane of the upper end of said recess,
said tie body having aligned seats extending
from the side walls of the tie body through
the walls of the recess at points diametri-
cally opposite on the latter, said seats lying
30 in the plane of the upper side of the said
- disc, and diametrically opposite upstanding
rail-engaging projections on said disc for
engaging with opposite sides of a rail rest-
ing upon said seats and extending diametri-
cally across said disc. 35
5. A combined tie and rail fastener com-
prising a body having a recess in the upper
side thereof adjacent to one end thereof, said
recess being circular in horizontal section,
a disc rotatably supported in said recess and
40 terminating at its upper end below the plane
of the upper end of said recess, said tie body
having aligned seats extending from the side
walls of the tie body through the walls of
the recess at points diametrically opposite
45 on the latter, said seats lying in the plane of
the upper side of said disc, diametrically op-
posite upstanding rail-engaging projections 50
on said disc for engaging with opposite sides
of a rail resting upon said seats and extend-
ing diametrically across said disc, and
spaced retaining members extending in-
wardly beyond the wall of said recess in 55
overlying relation to said disc to normally
prevent vertical displacement of the latter
from said recess, said disc having notches
in its periphery adapted to receive the ex-
tending portions of said retaining members
60 when the disc is in a certain position in the
recess, so that said disc then may be lifted
bodily from said recess.

HARVEY ZWINGLE MORGAN.
